UNITED STATES PATENT OFFICE

THOMAS F. LUUFFMAN, OF NEW YORK, N. Y.

SOFFIT CLIP

Application filed August 12, 1929. Serial No. 385,388.

This invention relates generally to clips and has particular reference to soffit clips used for reinforcing concrete or fireproofing material employed in connection with the structural framework of buildings.

One of the objects of the invention is the provision of a reinforcing element which, while partly contacting with and supported by a building framework member, is also spaced therefrom on different sides of the latter to reinforce, with a reduced amount of material, selected points of the concrete which encases such framework.

Another object of the invention is to provide a reinforcing unit which includes a series of parallel members of the above described character, each of which may be spaced from a framework structure, at least at one point, together with a single right angularly disposed member, which also acts as a reinforcement, and as a carrier for the parallel members.

With these and other objects in view, the invention resides in certain novel constructional features, the essential characteristics of which, hereinafter fully described, are particularly pointed out in the appended claims, and illustrated in the accompanying drawing, which shows embodiments of the invention as at present preferred, and in which:—

Figure 1 is a view in elevation of one form of soffit clip within the scope of my invention.

Fig. 2 is a transverse sectional view of a concrete-encased I-beam, showing a soffit clip of the type illustrated in Fig. 1 employed therewith.

Fig. 3 is a fragmentary perspective view illustrating a plurality of soffit clips in assembled relation with an auxiliary reinforcing element, and

Fig. 4 is a transverse sectional view of a concrete-encased channel beam showing a modified form of clip which may be employed therewith.

Referring particularly to the drawing by reference characters, the numeral 10 designates the clip of Figs. 1 to 3 in its entirety; this clip being formed of a single piece of

wire, represented in the preferred embodiment of the invention as being round in cross section, which wire is bent to provide the aligned portions 11 and a pair of opposed loops 12 therebelow, with a central portion 55 13, disposed in parallel relation with respect to the parts 11, and connected therewith by perpendicular portions 14, to form a bight between said loops; the latter being aligned with and having their lower portions in the 60 same plane as the portion 13 constituting the bight.

The wire of the clip is bendable and is provided with a pair of like terminals 16 which, rising from the loops 12, cross the portions 65 11 and may be attached thereto as by welding. When these terminals are bent inwardly, from the position shown by dot and dash lines in Fig. 1 of the drawing, to the position shown in full lines in said figure, the clip may 70 be placed on the end of a member of a framework construction, such as an I-beam 17, and moved along the beam to any desired position, since the portions 11 and the extreme 75 ends 18 of said terminals embrace the flange (or flanges) 19 of the beam with a slidably fit. But the portions 18 and 11 of the clip may be spaced further apart, so that the latter portions remain clear of the flange, while the ends 18 support the clip in the required 80 position during the pouring of concrete 20 into the usual forms surrounding the beam.

Any number of transverse members may be arranged in parallel relation and attached, as by the bights 13, to a longitudinally disposed member 21, which may be wire, as shown in Fig. 3. When a group of reinforcing clips, such as illustrated in Fig. 3 is applied to a beam from the end of the latter, the said clips may be moved along the beam 85 by one person, who may remain at the said end during the operation, thereby effecting a considerable saving in labor. The reinforcing unit or clip may also be applied directly 90 to a beam while the ends 18 are in the vertical position, after which the said ends may be bent inwardly above the flanges 19.

I find that in certain structures soffit clips made from "12" gage wire, with loops 12 about one inch in diameter, with the runs 13 consti- 100

tuting the bight portions disposed about one inch from the lower flange of the beam, with a space of about one inch between the inner part of each loop and the portions 11, and with terminals 16 of about three inches in 5 length, give good results, but wire of any other thickness and loops and bight portions of other dimensions may be used without departing from my invention. While the soffit 10 clips may be disposed about twelve inches apart on longitudinal connecting wires 21, which may be of "12" gage, the length of the portions 13 constituting the bights is subject to change and may be such as the width of the 15 beam flanges may require; another longitudinal wire or member, like the said member or wire 21, being used when necessary.

In Fig. 4 I have shown a slightly modified form of clip in which a terminal 16' is extended along the web of a channel beam 17', the terminal being bent at 22, and provided with an end 18' to be bent over and below a flange 19'.

The clip which is well suited for quantity 25 production, may be made by machinery, the wire 21 and the portion 13 at their intersections, and the portions 11 and 16 at their intersections, being welded, preferably electrically.

Having thus described my invention, I 30 claim:

1. A soffit clip comprising a length of wire having a bight portion, perpendicular portions at the ends of said bight portion and 35 continuous therewith, outwardly extending aligned portions continuous with said perpendicular portions and in a plane parallel with said bight portion, oppositely disposed loops continuous with said aligned portions; 40 said loops being spaced from said bight, and terminals continuous with and extending perpendicularly from said loops; said terminals being adapted to be turned inwardly over said aligned portions.

45 2. A soffit clip comprising a length of wire having a centrally disposed bight portion, perpendicular portions at the ends of said bight portion and continuous therewith, outwardly extending aligned portions continuous 50 with said perpendicular portions and in a plane parallel with said bight portion, oppositely disposed loops continuous with said aligned portions; said loops being aligned with and spaced from said bight, 55 and terminals continuous with and extending perpendicularly from said loops inwardly thereof and crossing said aligned portions; said terminals being adapted to be turned inwardly over said aligned portions 60 and the bight connecting the same.

65 3. A soffit clip comprising a length of wire having a pair of aligned portions in spaced relation, a central bight disposed intermediate 70 said aligned portions and continuous therewith, a loop on the outer end of each of

said aligned portions and below the same; the lower portions of said loops being aligned in the plane of said bight, and terminals extending from said loops perpendicular to the plane of said bight and adapted to be bent inwardly over said aligned portions. 75

4. A soffit clip comprising a length of wire having a central straight portion, outwardly disposed portions spaced from said central portion and in a plane parallel therewith, 80 interposed perpendicular portions connecting said central portion and the outwardly disposed portions, loops on the respective outer ends of said latter parts, and terminals rising from the inner sides of said loops perpendicular to said central straight portion and adapted to be bent inwardly over the same.

In testimony whereof I hereby affix my signature.

THOMAS F. LUFFMAN.
